UNITED STATES PATENT OFFICE.

JOSEPH SACHS, OF HARTFORD, CONNECTICUT, ASSIGNOR TO THE SACHS COMPANY, OF HARTFORD, CONNECTICUT, A CORPORATION OF CONNECTICUT.

SAFETY-FUSE TERMINAL.

No. 852,037.

Specification of Letters Patent.

Patented April 30, 1907.

Application filed March 9, 1906. Serial No. 305,089.

To all whom it may concern:

Be it known that I, JOSEPH SACHS, a citizen of the United States, residing at Hartford, in the county of Hartford and State of Connecticut, have invented an Improvement in Safety-Fuse Terminals, of which the following is a specification.

My invention relates to safety fuse contact terminals of the screw clamp contact type and particularly to the manner in which the terminals and the end caps of the safety fuse devices are secured together.

Heretofore in constructing safety fuses of the class to which the present invention relates, the fuse strips or the terminals thereof have been commonly passed through the end caps or ferrules and soldered or otherwise electrically connected to the clamp contact terminal of the fuse device, wherein one and the same connection served to connect the fuse strip or its terminals to the clamp terminals electrically and also to connect the clamp terminals and the end caps mechanically. In so assembling the parts, it has been necessary to employ jigs or other similar tools to properly center and aline the end caps and contact terminals and from the nature of the connection between these members, the completed fuse device is oftentimes not sufficiently rigid to withstand the strains to which the same is subjected in practice.

The object of my present invention is therefore not only to dispense with the employment of jigs or other similar tools in assembling the end caps and contact terminals, but also to unite these members in such a manner as to increase the rigidity of the connection, making the mechanical connection between the clamp contact terminals independent of the electrical connection between the fuse strip or its terminals and the clamp contact terminals.

In carrying out my invention I employ end caps adapted to fit over the casing of the fuse device and screw clamp terminals preferably angular, to which the inclosed fuse strip is electrically connected, one of these members being provided with lugs or ears and the other with suitable openings adapted to receive the said lugs or ears and through which the same are passed and connected to secure the said members together.

In the drawings:—Figure 1 is a plan of a fuse device fitted with terminals embodying

my present invention. Fig. 2 is an elevation of the same. Fig. 3 is an end view of my improved terminal. Fig. 4 is a section on line *x*, *x*, Fig. 3. Fig. 5 is an end view illustrating a modification of the invention. Fig. 6 is a section on line *y*, *y*, Fig. 5.

Referring to the drawing, *a* designates a casing which is provided with end caps *b* to which the fuse terminals *2* of the fuse strip *3* are electrically connected and preferably in suitably equi-distant positions, the end caps *b* are provided with holes *c*.

d designates the screw clamp contact terminals which are preferably angular, one part being provided with a suitable recess to receive the stationary terminal to which the fuse device is to be connected, and the other part of each terminal *d* is provided in equally spaced apart positions corresponding with those in which the holes *c* are placed in the end caps *b*, with lugs or ears *e* adapted to be passed through the said openings *c* in the end caps *b* and turned down or riveted against the inner sides thereof to connect the said end caps and terminal members together, and at the same time fix these parts in their proper alinement, the aperture *4* being adapted to receive the fuse strip terminal and in which the same is electrically connected to the contact terminal, or as indicated in Figs. 5 and 6, the faces of the end caps *b* may be provided with ears or lugs *f* preferably in equally spaced apart positions and equally distant from the center and the edges of one member of the terminals *d* provided with suitable notches *h* adapted to receive the ears or lugs *f* which are then turned down against the surface of the said member of the terminals *d* and in this instance as illustrated when four of the ears or lugs are employed, it will be necessary to provide the said members of each terminal *d* with suitable openings *h'* adapted to receive the fourth ear or lug *f* provided in the face of the end cap *b*.

I claim as my invention:

1. A safety fuse terminal comprising an end cap, a contact terminal and lugs or ears provided integral with one of said members, the other member being provided with holes through which the said lugs or ears are passed to secure the said members together.

2. A safety fuse terminal comprising an end cap, a contact terminal, lugs or ears on said terminal and integral therewith, the said

end cap being provided with holes through which the said lugs or ears are adapted to be passed and turned down to secure the said terminal and end cap together.

5. A safety fuse comprising an end cap and an angular screw contact terminal, and lugs on one part of said terminal, the face of the said end cap being provided in positions corresponding to the said ears or lugs with holes adapted to receive the said ears or lugs and through which the same are passed and turned down to secure the said terminals and end cap together.

4. A safety fuse terminal comprising an end cap, a contact terminal, both of which members are provided with an aperture for receiving and making electrical connection with a fuse strip or its terminal, and means connected with one of said members and independent of the said electrical connection for securing said members together.

5. A safety fuse terminal comprising an end cap, a contact terminal, both of which members are provided with an aperture for receiving and making electrical connection with a fuse strip or its terminal and means

connected with one of said members for securing the same to the other of said members independently of the said electrical connection and fixing the relationship of said members.

6. A safety fuse terminal comprising an end cap, a contact terminal and lugs or ears provided integral with one of said members, the other member being provided with means for receiving the said lugs or ears and by which the relationship of said members is fixed.

7. A safety fuse terminal comprising an end cap, a contact terminal, both of which members are provided with means for receiving and making electrical connection with a fuse strip or its terminal, and means connected with one of said members and independent of the said electrical connection for securing said members together.

Signed by me this 16th day of February 1906.

JOSEPH SACHS.
